UNITED STATES PATENT OFFICE.

THOMAS NANCE, OF SHELBYVILLE, TENNESSEE.

PEN-HOLDER.

SPECIFICATION forming part of Letters Patent No. 447,197, dated February 24, 1891.

Application filed September 10, 1890. Serial No. 364,581. (No model.)

To all whom it may concern:

Be it known that I, THOMAS NANCE, a citizen of the United States, residing at Shelbyville, in the county of Bedford and State of Tennessee, have invented certain new and useful Improvements in Pen-Holders, of which the following is a specification.

My invention relates to devices for holding ordinary writing-pens, and is adapted for use on almost any kind of a pen-stock, but more especially for the ordinary wooden stocks and common folding or pocket holders; and it consists in certain peculiarities of the construction and arrangement of the different parts of the same, as will be hereinafter more fully set forth, and specifically claimed.

The objects of my invention are to provide a holder for pens which shall be neat in appearance, strong and durable, and quite inexpensive, and into which the shank of the pen can be more easily inserted or removed than from the ordinary holders now in use, and also to impart or allow to the pen an oscillating elastic and yielding movement when it is applied to the paper in writing, thus affording ease to the penman and preventing weariness and cramp to the hand, or what is known as "scribes' paralysis." I attain these results by the use of the peculiar mechanism illustrated in the drawings; and in order to enable others skilled in the art to which my invention pertains to make and use the same I will now proceed to describe it, referring to the accompanying drawings, in which—

Figure 1 is a view in side elevation of my holder secured to a stock and with a pen in place ready for use. Figs. 2, 3, and 4 are detail views of the different parts of the holder, showing them separately and detached from the stock. Fig. 5 is a sectional view taken on line $x-x$ of Fig. 1, and Fig. 6 is a side view of two of the parts together.

Similar letters refer to corresponding parts throughout the different views of the drawings.

A represents an ordinary stock, to one end of which is secured in the customary manner a hollow tube B, which may be made of any suitable material and of proper size to suit the stock and pen. The lower end of the tube B is preferably formed as at a—that is, has its upper and lower portion cut away,

as shown, to allow the pen to yield in a downward or upward movement, as will be presently more fully explained. Near this end of 55 the tube is provided in either side thereof a hole c for the reception and retention of a small rivet or pin c^3 , which secures the pieces C and D in their proper positions within the hollow free end of the tube B, and for this 60 purpose each of the pieces is formed with similar holes c' through its sides. As shown in the drawings, the piece C is made of sufficient size to fit snugly in the hollow of the tube B, yet with sufficient laxity to permit of 65 a slight vertical movement of the piece C, the upper end of which is formed into or provided with a flat or blade spring d, which is deflected, as shown in Fig. 3, or may be bent back upon itself, and when in position in the 70 tube B rests against the inner lower side thereof, as shown by dotted lines in Fig. 1.

The piece D is a short split tube which fits into the hollow of the tube C, and is usually made of elastic or flexible metal or other material, and has near its upper end holes c^2 for the pin c^3 , which pivotally secures it and the piece C to and within the tube B.

It will be seen in Figs. 4 and 6 that the piece D is cut away at its inner end, as at e, 80 and projects slightly beyond the front end of piece C, thus permitting the shank of the pen to be easily inserted between the inner periphery of the piece C and the outer one of piece D, the shank of the pen being first 85 placed on the projecting end of piece D and then pressed back into place, the cut-away portion e allowing the piece to be tipped forward, thus making the insertion or extraction of the pen an easy matter, as will be 90 readily understood. It is also apparent that the piece D, being made in the form of a split tube and of elastic material, will readily yield when a pen is placed between it and the piece C, yet by reason of its flexibility will retain 95 the pen firmly in place.

In order to afford greater expansion and contraction to the piece D, which acts as a spring, I may form the holes c^2 slightly elongated, as shown, and thus accommodate pens 100 of different sizes and those having shanks of different thicknesses.

To carry my invention into effect, I place the tube B on the end of a stock and insert

in the open end thereof the piece C, which has inserted in its open end the piece D. The three pieces are then secured together by means of the pin c^3 , passing through the holes c c^2 . The pen is then inserted, as above stated, and the device is ready for use. When the point of the pen is pressed on the paper, the piece C, being pivotally secured, as set forth, will yield, and by reason of the spring d will afford a soft yielding movement of the pen, which is so much desired by writers.

What I claim is—

1. A pen-holder consisting of the tube B, having the holes c , the piece C, having holes c' and spring d , and the split tube D, having the openings c^2 and inserted in the piece C, the pieces B, D, and C being pivotally secured together by and having the pin c^3 , substantially as and for the purpose set forth.
2. As an improved article of manufacture, a pen-holder consisting of a stock, a tube B, having the holes c and cut away, as at a , the piece C, having the holes c' and spring d , and

the split tube D, having the opening c^2 and cut away, as at e , the pieces B, C, and D being pivotally secured together by and having the pin c^3 , all constructed, arranged, and operating substantially as and for the purpose set forth.

3. As an improved article of manufacture, 30 a pen-holder consisting of a stock, a tube B, having the holes c and cut away, as at a , the piece C, having the holes c' and spring d , and the split tube D, having the elongated openings c^2 and cut away, as at e , the pieces B, C, 35 and D, being pivotally secured together by and having the pin c^3 , substantially as and for the purpose set forth.

In witness whereof I have hereunto set my hand and affixed my seal this 12th day of 40 July, 1890.

THOMAS NANCE. [L. s.]

In presence of—

JOHN W. FRIERSON,
OLIVER COWAN.
